By his Attorney

Chas. E. Gile

UNITED STATES PATENT OFFICE.

MORDUCH L. KAPLAN, OF BROOKLYN, NEW YORK.

ELECTRIC-BATTERY LAMP.

Application filed July 27, 1921. Serial No. 487,833.

To all whom it may concern:

Be it known that I, MORDUCH L. KAPLAN, a citizen of the United States, and a resident of Brooklyn, in the county of Kings and State of New York, have invented certain new and useful Improvements in Electric Battery Lamps, of which the following is a specification.

The invention pertains more particularly to a class of electric battery lamps possessing a battery and a miniature electric lamp bulb and adapted to stand on a table or the like. The object of my invention is to simplify, cheapen and extend the use of electric battery and candle lamps and to provide an electric candle lamp comprising two main units, to-wit, a vertical plural-cell battery and a cap or top member detachably applied thereto and carrying the lamp bulb. In carrying out my invention I extend the negative pole of the lower cell of the plural-cell battery to the upper end of the battery and construct the cap to pass into electrical engagement with said negative pole on the application of the cap to position over the battery. The lamp bulb carried by the cap has one terminal in electrical connection, through the cap, with the negative pole of the battery and the other terminal in electrical connection with the positive element of the upper cell of the battery. The lamp bulb may be used as the switch for making and breaking the circuit, said lamp bulb when screwed upwardly breaking the circuit and when screwed downwardly, completing the circuit and causing the lighting of the lamp. When the battery has become exhausted, the cap is removed therefrom and placed upon a new battery, thus restoring the candle lamp for further use. In accordance with my invention I dispense with the metallic casings which usually receive the battery of electric candle lamps and provide a candle lamp consisting essentially of the plural-cell battery and the detachable cap or dome or like top member, the cap being equipped with a socket to receive the lamp bulb and, when necessary, a conductive filler interposed between the lower terminal of the lamp bulb and the positive element of the battery.

My invention may be carried into effect in several modified forms, two of which I have illustrated in the drawings.

The invention will be fully understood

from the detailed description hereinafter presented, reference being had to the accompanying drawings, in which:

Fig. 1 is a central vertical section through an electric battery lamp constructed in accordance with and embodying my invention;

Fig. 2 is a side elevation of the battery separated from its exterior covering material and the superimposed cap, Fig. 2 illustrating the battery within its pasteboard carton and showing the manner of connecting the negative pole of the lower cell of the battery with a suitable contact above the battery to be engaged by the cap;

Fig. 3 is a detached perspective view of a conducting filler device which I place within the cap to become interposed between and engage the lower terminal of the lamp bulb and the positive element of the battery;

Fig. 4 is a detached top view of the battery and its enclosing pasteboard carton;

Fig. 5 is a detached vertical section of the cap, taken at a right angle section of Fig. 1, and

Fig. 6 is a vertical section through the upper portion of an electric battery lamp embodying a modification of my invention.

In the drawings, referring to Figs. 1 to 5 inclusive, illustrating one embodiment of my invention, 10, 11 designate the cells of the battery, one cell being placed above the other in series and the whole constituting a vertical plural-cell battery. The negative or zinc pole of the cell 11 engages the carbon pole of the cell 10, and said cells in the completion of the battery are enclosed in a pasteboard cylinder or the like 12 which insulates and keeps the cells together and permits them to be handled as a single battery. The cells 10, 11 are slipped endwise into the cylinder 12, which snugly receives said cells. The cylinder or carton 12 is of customary durable stiff character, except that in the present instance I extend it above the upper end of the battery to receive a superimposed cap or dome 13 having in its upper end a threaded depending metal sleeve 14, which may be secured to the cap or dome 13 by a line of solder 15 or formed integrally therewith and receives the neck of the usual miniature lamp bulb 16. The sleeve 14 is, as usual, in electrical connection with one terminal of the bulb 16.

The cylinder or carton 12 is provided at opposite sides of its upper end and above

the battery with inwardly extending pins or rivets 17 which are of conducting material and serve to receive and interlock with a lower sleeve portion 18 of the cap or dome 13, said sleeve portion 18 being provided with bayonet slots 19, as shown in Fig. 5, to be engaged with the pins 17.

The negative pole of the lower cell 10 is carried upwardly above the battery by 10 means of a conducting wire 20 which is soldered, at 21, to the zinc of the cell 10 and at its upper end is soldered, at 22, to the adjacent pin 17.

The cap or dome 13 is preferably made of 15 candle shape, said cap or dome in its upper portion being of general conical outline and having sides which curve downwardly and outwardly to an annular shoulder 23 formed by beading the interior of the cap below its 20 upper section. The annular beading 23 provides a groove to receive the edges of a disk 24 of fibre or other insulating material and likewise imparts a finish to that portion of the cap or dome which is directly above 25 the upper edge of the cylinder or carton 12. The annular shoulder 23 constitutes a dividing line between the upper conical shaped portion of the cap or dome 13 and the depending sleeve or skirt portion 18 of said cap 30 or dome.

The disk 24 has secured upon its upper and lower sides by rivets 25, hollow metal caps 26, 27 which correspond with each other and are flanged to engage and be 35 riveted to the disk 24. The disk 24 and caps 26, 27 constitute a conductive filler which I apply within the cap or dome 13 so as to bridge the space between the lower terminal of the lamp 16 and the positive 40 element 28 of the battery cell 11. The negative pole of the battery is connected by the wire or conductor 20 with one of the pins 17 and hence is in circuit through the cap or dome 13 with the sleeve 14 and the neck 45 or one terminal of the lamp 16, while the positive element 28 of the battery is in electrical connection through the caps 26, 27 with the lower terminal of the lamp 16.

In assembling the parts of the electric 50 battery lamp, the bulb 16 may be screwed into the sleeve 14 and the cap or dome 13 may, after receiving the disk 24 and its parts, be applied upon the upper end of the battery by inserting the sleeve portion 18 55 of said cap or dome downwardly within the upper end of the cylinder or carton 12 with the vertical members of the slots 19 passing downwardly over the pins or rivets 17, after which the cap or dome will be 60 locked in position by giving it a partial turn so as to carry horizontal portions of the slots 19 upon the pins or rivets 17.

In my construction of electric battery 65 lamp I preferably employ the lamp 16 as the means for making and breaking the cir-

cuit or as a switch. When the lamp 16 is screwed upwardly to a slight extent so as to free the lower terminal thereof from the upper end of the cap 26, the circuit will be broken, because then the lower terminal of 70 the lamp is not in electrical connection with the positive element 28 of the battery. When it is desired to complete the circuit and cause the lighting of the lamp, the bulb 16 will be screwed downwardly until its 75 lower terminal engages the cap 26, whereupon the circuit will be completed and the lamp will light.

The pasteboard cylinder or carton 12 will 80 preferably be covered over by an ornamental paper or the like 29 so as to add a finish to the article and render it suitable to be placed on a dining table or elsewhere as a candle lamp. The lower end of the battery is broad and serves as a base on which the 85 candle lamp may stand without the requirement of the expensive stands at present in use in connection with candle lamps. The battery composed of the vertical cells 10, 11 should be tightly held by the cylinder or 90 carton 12 so as not to at any time, even in the absence of the dome or cap, slide through the same. In the present instance the cylinder or carton 12 not only tightly 95 fits around the battery cells, but is further secured with relation thereto by the conducting wire or strip 20, which in itself will prevent the battery cells from slipping through the cylinder or carton 12.

In Fig. 6 I illustrate a modified form of 100 cap or dome to be superimposed over the battery and engaged with the pasteboard cylinder or carton 12. The carton 12 of Fig. 6 is provided with the conducting pins or rivets 17 hereinbefore described, and the 105 cap or dome, numbered 30 in Fig. 6, is formed with a depending skirt portion 31 having bayonet slots to engage the pins 17, the same as the cap or dome 13 is fastened in position. In the construction shown 110 in Fig. 6 the cap or dome 30 is dished downwardly at its upper end, as at 32, to represent a candle which has been partly consumed or to imitate the upper end surface 115 of a wax candle which has been burned down at its upper tapered end by use. The cap or dome 30 is formed with a depending threaded metal sleeve 33 to receive the lamp 34 and enter into electrical engagement with the side terminal thereof. By reason 120 of the dishing downwardly of the upper end of the cap or dome 30, the lower terminal of the lamp 34 may directly engage the positive element 28 of the battery cell 11, and by reason thereof the conductive 125 filler shown in Figs. 1 and 3 may be omitted, said filler being required because of the elevation of the lamp 16 in Fig. 3 from the positive element 28 of the battery cell. The 130 circuit in the construction shown in Fig. 6

is made or broken by screwing the lamp 34 against the positive element 28 or upwardly from engagement therewith.

In both forms of my invention I provide 5 a candle lamp of desirable character and dispense with expensive stands for the same and also avoid the necessity for special switches in making and breaking the circuits; since I utilize the lamp bulb itself for 10 that purpose. The cap or dome 13, shown in Fig. 1, is an approximate imitation of the upper end of a wax candle which has not been in part consumed, whereas the cap or dome shown in Fig. 6 is in approximate 15 imitation of the upper end of a wax candle which has been in part consumed by use.

In both forms of my invention I propose 20 that the cap or dome portion thereof shall be of metal and applied to a new battery whenever a battery in use has become exhausted, it being my purpose that when a battery becomes exhausted, it may be thrown away and replaced by a new battery of the same kind, to which the candle features described 25 may be readily attached.

An obvious modification of my invention and wholly embodying the same would consist 30 in merely reversing the battery or turning it upside down within the carton 12, in which event the lamp bulb when screwed downwardly would pass into electrical connection with the negative pole of the then upper cell and the conductor 20 at its lower end would be connected with the opposite or 35 positive pole of the then lower cell.

My invention admits of modification in the details of its several parts, and hence I do not confine the invention to all of the details shown and described, further than 40 the appended claims may require, and desire to receive adequate protection for the same.

What I claim as my invention and desire to secure by Letters-Patent, is:—

45 1. An electric battery lamp of the character described, comprising a vertical plural cell battery, a non-conductive durable carton which receives said cells endwise and snugly encloses them and extends above the 50 upper cell, leaving a substantial space within the upper end of said carton above the battery, a removable conductive cap having a skirt portion snugly fitting within the upper end of said carton above the battery, said cap having a depending central socket for and carrying therein an electric lamp de-

tachably applied to said socket and having one terminal positioned for electrical connection with one pole of the battery, a conductor secured to the opposite pole of the 60 lower cell of the battery and thence extending to the upper end of the battery and being there secured in position to become electrically engaged with said cap upon the application of the cap to position, and means 65 within the aforesaid space releasably locking the skirt portion of said cap within the upper end of said carton and in fixed electrical connection with said conductor, said lamp serving as a make and break 70 switch.

2. An electric battery lamp as claimed in claim 1, in which the means releasably locking the skirt portion of the cap within the upper end of the carton and in electrical connection with said conductor, comprises pins secured in the sides of said 75 carton and projecting into the space above the battery and to one of which said conductor is connected and bayonet slots formed 80 in the skirt of said cap and adapted for engagement with said pins.

3. An electric battery lamp of the character described, comprising a vertical plural cell battery, a non-conductive durable carton 85 which receives said cells endwise and snugly encloses them and extends above the upper cell, leaving a substantial space within the upper end of said carton above the battery, a removable conductive cap closing 90 the upper end of the carton and dished downwardly and having a depending central socket entering the aforesaid space and carrying an electric lamp detachably applied in said socket and positioned for electrical 95 connection with one pole of the battery, said lamp constituting a make and break switch, a conductor secured to the opposite pole of the lower cell of the battery and thence extending continuously to the upper end of 100 the battery and being there secured in position to become electrically engaged with the peripheral portion of said cap upon the application of the cap to position, and concealed means within the aforesaid space releasably securing the cap in position on the carton and in fixed electrical connection with said conductor.

Signed at New York city, in the county of New York and State of New York, this 110 25th day of July A. D. 1921.

MORDUCH L. KAPLAN.
